UNITED STATES PATENT OFFICE.

LESTER J. McNUTT, OF JEFFERSON, OHIO.

APPARATUS FOR MAKING CARBON AND GENERATING STEAM.

Application filed February 10, 1926. Serial No. 87,296.

In making gas black it is usual to direct a gas flame against a surface on which the unconsumed carbon is deposited. The method as usually employed is wasteful in that the entire heat from the gas flame is lost and further the full possibilities of carbon deposit are not attained.

The waste of gas in the ordinary processes is such that many States limit or prohibit the use of gas in the formation of gas black on the theory that the loss of the possible heat from such quantities of gas is detrimental to the State.

In the present invention there is an endeavor to conserve this heat which has been wasted in the generating of steam which may be used for power, or heating purposes, thus conserving heat from the gas which has heretofore been wasted. Features and details of the method will appear from the specification and claims.

The apparatus performing the subject matter of the invention is illustrated in the accompanying drawings as follows:

Fig. 1 shows a section on the line 1—1 in Fig. 2.

Fig. 2 a plan of the apparatus.

Fig. 3 an end view, partly in section, on the line 3—3 in Fig. 1.

Fig. 4 a section of one of the generator units on the line 4—4 in Fig. 3.

Fig. 5 a section on the line 5—5 in Fig. 3.

1 marks the frame of the machine, and 2 the generating cylinders which are preferably in the form of a battery, four being shown in the drawings. These generator cylinders are similar in construction, each having the heads 3 and 4 from which trunnions 5 and 6 respectively extend. The trunnions are mounted in bearings 7 on the frame so that the cylinders may be rotated. Gears 8 are mounted on the several trunnions and these gears are in mesh. A worm gear 9 is mounted on one of the trunnions and this is driven from a worm 10 from any convenient source of power so that the cylinders are rotated.

A water pipe 11 extends through the trunnion 5, a stuffing box being provided for forming a steam tight joint. The pipe 11 discharges through the lower end of a fitting 17 within the generator. The outer end of the pipe 11 is connected with a manifold 12 in which is arranged a controlling float 13 operating on a float valve 14. Water is delivered from the supply pipe 15 to the

manifold 12. The purpose of the float is to control the inflow of water so as to maintain a constant level in the steam generator. Any well-known means may be adopted for this purpose.

A steam pipe 16 extends along the top of the generator. It is supported at a dead end in the fitting 17 and the opposite end extends into a connecting fitting 18. The steam pipe is supplied with a series of perforations 16^a along its upper portion for receiving steam from the generator. The fitting 18 is connected with a pipe 19 which extends through the trunnion and a stuffing box 20. The pipe 19 is connected to a manifold 21 which connects all of the generators and the manifold leads to a steam pipe 22 which leads to a point of use.

Gas burners 23 are arranged under each of the generators, these burners ordinarily being arranged in pairs and directing their flames 24 radially against the walls of the generator. The burners are connected to the gas manifold 25 which receives its supply from a gas supply pipe 26.

A hopper 27 extends under the generators and is carried by the frame. It leads to the conveyor pocket 28 in which there is a conveyor screw 29 which carries the accumulated gas black to a discharge pipe 28^a at the end of the conveyor.

Scrapers 30 are mounted over the cylinders. These scrapers are pivotally mounted on rods 31 extending lengthwise above each cylinder and these rods are mounted in cross bars 32. A reciprocating bar 33 is pivotally mounted at 33^a on the cross bar 32. The bar terminates in a reversing gear loop 34 having the external longitudinal guides 35 and the two-sided rack 36 along the central guide bar 38. A pinion 37 meshes with the rack 36, the hub of the pinion extending upwardly into guiding contact with the guide bar 38. The guide sides 34 have the end turns 40 and the guide bar 38 terminates in spaced relation to the end turn. There is thus formed a guide slot 39 extending entirely around the bar 38. The gear is mounted on a shaft 41, the end of which extends into the slot and operates against the guide 35. This shaft end and the gear hub acting on the walls of the slot 39 control the movement so that as the gear is rotated and reaches the end of the rack it swings the loop to the reverse side of the gear and continues down the opposite side

of the rack, thus giving a reciprocating movement to the bar 33. This is the ordinary mechanical movement and any device providing reciprocating movement may be used. The shaft 41 is mounted in bearings 42. A pinion 43 is arranged at the lower end of the shaft and meshes with a gear 44 on a conveyor shaft 46. A sprocket 45 is also mounted on the shaft 46 and a sprocket 10 chain 47 extends from the sprocket 45 to a sprocket 45^a on one of the trunnions 6. Thus both the reciprocating movement for the scrapers and the rotary movement for the conveyor is driven through this mechanism.

15 Gore-shaped deflectors 48 are arranged between the upper parts of the generator cylinders. These deflectors are supported by posts 49. These deflectors have surfaces 50 which are practically parallel with the walls of the cylinders so that these surfaces are traversed by the scrapers 30. The deflectors preferably have openings 51 which are connected by pipes 52 with a manifold 53 leading to an air blast supply so that 20 these are cooled. The carbon-laden gas moving around the cylinders striking these deflectors adds to the deposit of carbon from the gas plant. As the carbon accumulates it is scraped off by the scrapers both from 25 the cylinders and the deflectors and falls into the hopper as above described.

By this means, the method and apparatus, the carbon deposit from the gas is increased by reason of the proper cooling of the 30 depositing surfaces and the heat generated by the burned gases is conserved through the generation of steam in the cylinders.

What I claim as new is:—

1. In a carbon making and steam generator apparatus, the combination of a gas 40 burner; a steam generating cylinder receiving the flame from the burner upon its wall; bearings for the cylinder; a steam discharge pipe extending along the top of the cylinder and receiving the steam therefrom, said discharge pipe being supported by and extending through the bearing of the cylinder; and means removing and collecting the carbon deposit upon the cylinder.

50 2. In a carbon making and steam generator apparatus, the combination of a gas burner; a steam generating cylinder receiv-

ing the flame from the burner upon its wall; 55 bearings for the cylinder; a steam discharge pipe extending along the top of the cylinder and receiving the steam therefrom, said discharge pipe being supported by and extending through the bearing of the cylinder; means introducing water to the cylinder at the axis and opposite end of the cylinder from the bearing carrying the steam discharge pipe; and means removing and collecting the carbon deposit upon the cylinder.

3. In a carbon making and steam generating apparatus, the combination of a gas burner; a steam generator comprising a chamber receiving the flame from the burner upon its wall; means confining and conveying the steam generated; a gas deflector adjacent to the chamber; and means removing and collecting the carbon deposit on the chamber and the deflector.

4. In a carbon making and steam generating apparatus, the combination of a gas 75 burner; a steam generating cylinder receiving the flame from the burner upon its wall; a scraper operating upon the cylinder for removing the carbon deposit therefrom; and a deflector adjacent to the cylinder and having a wall traversed by the scraper.

5. In a carbon making and steam generating apparatus, the combination of a gas burner; a steam generating cylinder receiving the flame from the burner upon its wall; 85 a scraper operating upon the cylinder for removing the carbon deposit therefrom; a deflector adjacent to the cylinder and having a wall traversed by the scraper; and means for cooling the deflector.

6. In a carbon making and steam generating apparatus, the combination of a plurality of steam generating cylinders; gas 95 burners directing their flames on the walls of said cylinders; a common driving means for rotating said cylinders; gore-shaped deflectors arranged between the cylinders; and a common driven carbon deposit removing and collecting apparatus operating on said cylinders and deflectors.

In testimony whereof I have hereunto set my hand.

LESTER J. McNUTT.
